UNITED STATES PATENT OFFICE

106,311

DESIGN FOR A PAPER CUP HOLDER

Eugene J. Lux, New York, N. Y.

Application July 30, 1937, Serial No. 70,750

Term of patent 14 years

To whom it may concern:

Be it known that I, Eugene J. Lux, a citizen of the United States of America, residing in the city, county, and State of New York, have invented a new, original, and ornamental Design for a Paper Cup Holder, of which the following is a specification, reference being had to the accompanying drawing, forming a part thereof.

In the drawing:

I claim:

The ornamental design for a paper cup holder substantially as shown.

EUGENE J. LUX.
